UNITED STATES PATENT OFFICE.

ALBERT KRAUTH, OF HAMILTON, OHIO.

AUTOGRAPHIC REGISTER.

SPECIFICATION forming part of Letters Patent No. 766,267, dated August 2, 1904.

Application filed March 8, 1904. Serial No. 197,191. (No model.)

To all whom it may concern:

Be it known that I, ALBERT KRAUTH, a citizen of the United States, residing at Hamilton, in the county of Butler and State of Ohio, 5 have invented certain new and useful Improvements in Autographic Registers, of which the following is a specification.

My invention relates to an autographic register, and in particular to that kind known as 10 a "summary" device, in which the record-sheet is adapted to receive only the totals.

One of the objects of the invention is to produce an improved feed.

Another object of the invention is to provide 15 a trip for releasing the tension of various feed-rollers.

The features of my invention are more fully set forth in the description of the accompanying drawings, forming a part of this specification, in which—

Figure 1 is a side elevation of a portion of an autographic register containing my improved summary device. Fig. 2 is a section on line *xx*, Fig. 1. Fig. 3 is a section on 25 line *ww*, Fig. 2. Fig. 4 is a section on line *rr*, Fig. 2. Fig. 5 is a central vertical section through the rolls, showing the check-indication mechanism. Fig. 6 is a front elevation of the same. Fig. 7 is a bottom plan 30 view of the means for supporting one of the record-rolls. Fig. 8 is a section on line *yy*, Fig. 7.

The relative positions of the delivery-strip and the record-strip are indicated in Fig. 5. 35 1 represents the casing, in the sides of which is journaled the shaft 2.

3 represents a main feed-roll mounted on shaft 2.

5 represents a companion feed-roll, the ends 40 4 of which journal in the blocks 6 in the slide-box 7 in the casing 1. They are held normally downward by the spring 8, so that the roll 5 frictionally contacts the roll 3.

9 represents a record-feeding roller; 10, the 45 shaft thereof, journaled in the casing. 11 represents a companion record-feeding roller contacting roller 9. These feed-rollers 9 and 11 feed the recorded strip into a suitable compartment within the register.

50 12 represents the shaft for roller 11. Said

shaft is journaled in the ends of arms 13 of the swinging frame 14. (See Figs. 5, 7, and 8.)

15 represents a shaft the ends of which are supported in the casing. The swinging frame 14 is hinged on shaft 15. 55

16 represents a coil-spring, one end of which is fixed to shaft 15, and the intermediate portion of the spring is looped around a tongue 17 of the frame 14. The function of the spring is to exert an upward tension on the 60 frame 14, holding the roller 11 in contact with roller 9.

In order to raise the roller 5 from contact with the roller 3 and at the same time to depress the roller 11 from contact with roller 9, 65 I provide the following devices: (see Fig. 4.)

At each end of the casing is a set of tripping mechanisms, one end being shown in Fig. 4, in which 18 represents a tripping-lever hinged at 19 to the casing. The upper end of the trip 70 18 engages the ends 4 of the roller 5. The slide-box 7 is provided with the slots 20, which permit the roller 5 to be raised. 21 represents another trip-lever, which is fulcrumed on the shaft 10. The upper end of the trip 75 21 engages the lower end of trip 18. The lower end of trip 21 engages the shaft 12. 22 represents a rock-shaft journaled in the casing. 24 represents rock-arms loosely journaled on shaft 22, having the lugs 23 engaging 80 the trip 18, said rock-arms being provided with an operating-rod *u*, by means of which they are rocked on shaft 22 to operate the trips 18 and 21 for simultaneously separating the two sets of feed-rollers. When this handle is raised, the trips 18 and 21 are rocked on their centers, overcoming the tension of the springs 8 and 16 and raising roller 5 and depressing roller 11 simultaneously. The 85 arms 24 can be rocked to throw the lug 23 beyond the dead-center, and so holding the rollers in separated condition for manipulating the paper strips which pass between them.

When the arms 24 are released, the springs 8 and 16 will return the rollers 5 and 11 to normal contacting positions with their companion rollers 3 and 9, respectively. 90

25 represents a ratchet-wheel on shaft 10. (See Fig. 4.)

26 represents a pawl pivoted to the casing, 100

the end of which pawl engages the ratchet-wheel 25. 27 represents a spring engaging the pawl 26.

28 represents the top of the writing-tablet. 5 (See Fig. 5.) The top or delivery strip of paper passes from the top of the tablet between the feed-rollers 3 and 5.

29 represents an idle roller journaled in the casing opposite end of the tablet 28. The 10 record-strip takes a downward course from the tablet over the roller 29, thence downward between the roller 3 and the curved plate 30 and between the rollers 9 and 11.

I will now describe the mechanism for respectively feeding the rollers. (See Figs. 1 and 2.)

31 represents a shaft outwardly projected from the casing 1. Upon this shaft is loosely mounted the crank 32.

20 33 represents a cap secured over the outer end of the shaft 31 and against the outer face of the fulcrumed portion of crank 32. Shaft 31 is non-revolute, and the cap 33 is secured thereto by the screw 34. Within this cap 33 25 and around the end of shaft 31 is a coil-spring 35, one end of which is fixed to the fulcrumed portion of the crank 32 and the other end to the cap 33. As this cap is a stationary element and the crank 32 is a movable element 30 connected together by a coil-spring, it follows that when crank 32 is moved on shaft 31 a given arc the spring will automatically reciprocate the crank to its initial position.

36 represents the handle of the crank. The 35 other end of the crank is provided with a sleeve 37, in which is mounted a coil-spring 38.

39 represents a pawl, one end of which is stemmed within the coil-spring 38, the other end of which pawl engages the teeth of the 40 ratchet-wheel 40, loosely mounted on shaft 31. The crank is provided with the peripheral flange 41, forming a housing around the ratchet-wheel 40. Upon the hub of the ratchet-wheel 40 is fixed a gear-wheel 42.

45 43 represents a plate secured to the casing by screws. One end of the shaft 2 of the roller 3 projects through the casing 1 and also through plate 43.

45 50 represents a pinion fixed to the shaft 2 and intermeshed with the gear-wheel 42. Upon the inside of the casing 46 represents another pinion fixed to the shaft 2.

47 55 represents a pinion fixed upon the shaft 10. Upon the hub of the pinion 47 is fixed a gear-wheel 48 in mesh with the pinion 46. One end of the shaft 12 projects beyond the arm 13 of the swinging frame 14, and upon the end of said shaft 12 is fixed a gear-wheel 49, intermeshed with the pinion 47.

60 50 represents a stop-lug on the outside of the casing, which engages the front end of the crank 32.

51 represents a second stop on the casing to engage the rear end of the crank 32. When 65 the crank 32 is raised, as indicated in dotted

lines, Fig. 1, the pawl 39 will fix into the teeth of the ratchet-wheel 40, so as to turn the ratchet-wheel with the crank, and rotation will be imparted from the gear-wheel 42 to the pinion 45, so rotating the shaft 2. From 70 the shaft 2 motion is conveyed to the roller 11 through the back gearing formed by the pinion 46, compound gear members 47 48, and the driven pinion 49. Thus the rolls 9 and 11 are driven at a relatively slower speed than 75 the rollers 3 and 5. This slower speed of the record-feeding rollers is for the purpose of feeding a short amount of record-strip to a larger amount of delivery-strip. When the crank 32 is released, the spring 34 will automatically return it to place, during which return movement the pawl 39 passes loosely over the teeth of ratchet-wheel 40, and so suspending the transmission of feed to the roller. The length of stroke of the crank 32, and 80 therefore the length of the paper strips to be delivered and recorded, is determined by the relative positions of the stops 50 and 51. As shown, I have arranged these stops to give the crank a movement practically equal to the 85 semicircle.

The rock-shaft 22 is provided with two arms 56, in the ends of which are pivoted the inwardly-projecting punches 57. (See Figs. 5 and 6.) The curved plate 30 is provided with 90 notches or recesses 58 for the entrance of the punches 57. The rocking of the shaft 22 rocks the arms 56, moving the punches 57 inwardly, so that the inner ends pass into the recess 58, perforating the record-strip by this 100 movement, and thus positively indicating the opening of the register-door. The roller 3 is cut out at 60 (see Fig. 2) to provide space for the punches 57.

61 represents a coil-spring around the rock-shaft 22, one end being fixed to shaft 22 and the other end fixed to the casing. The rock-shaft is rocked independent of rock-arms 24 to operate punches 57 by manipulating lever b.

63 represents a cutter-blade.

Having described my invention, I claim—

1. In an autographic register, a casing, two pairs of feed-rollers journaled therein, a crank, gear-wheels between the crank and the first pair of feed-rollers, gear-wheels between the 115 first pair and second pair of rollers, a pawl-and-ratchet mechanism, between the crank and gear-wheels, a spring for reciprocating the crank, and a stop mechanism for limiting the stroke of the crank, substantially as described.

2. In an autographic register, a pair of feed-rollers, a shaft on the outside of the casing, a crank loosely mounted on the outer end of said shaft, a ratchet-wheel loosely mounted on the shaft on the outside of the casing, transmitting devices on the inside of casing between the ratchet-wheel and one of said rollers, a spring-controlled pawl mounted on the crank, adapted to engage the teeth of the 120 125 130

ratchet-wheel, whereby it is fixed to the crank in one direction of rotation, substantially as described.

3. In an autographic register, a pair of feed-
5 rollers and a second pair of feeding-rollers, a
shaft, a crank loose thereon, a ratchet-wheel
loose on the shaft, a spring-controlled pawl
on the crank adapted to engage the ratchet-
wheel in one direction, transmitting devices
10 between ratchet-wheel and one of said rollers
of the first-named pair, transmitting devices
between said first-named rollers and one of said
rollers of the second-named pair, a spring for
reciprocating the crank and a stop mechanism
15 for limiting the stroke of the crank, sub-
stantially as described.

4. In an autographic register, a pair of feed-
rollers, the axis of one of said rollers projecting
through the casing, a second pair of feed-
20 rollers journaled in the casing, a train of gear-
wheels on the inside of the casing connecting
the two pairs of feed-rollers, a stud-shaft on
the outside of the casing, a ratchet and gear-

wheel thereon, a spring-controlled crank and
pawl on said stud-shaft, and a gear-wheel on
25 the shaft of the feed-roller upon the outside
of the casing intermeshed with the gear-
wheel, driven by said ratchet on the stud-shaft,
substantially as described.

5. In an autographic register, a pair of de-
30 livery feed-rollers, one of which is held in
yielding contact with the other, a pair of rec-
ord-receiving rollers one of which is held in
yielding contact with its companion, trip-le-
vers having meeting ends, the outer ends of 35
said levers engaging said shiftable rollers re-
spectively, a tripping-lug engaging one of said
levers, and means for rocking said lug for
simultaneously shifting said rollers, substan-
tially as described. 40

In testimony whereof I have hereunto set
my hand.

ALBERT KRAUTH.
